UNITED STATES PATENT OFFICE.

JEREMIAH E. MATHEWSON, OF SHEFFIELD, COUNTY OF YORK, ENGLAND.

SAND-BLAST APPARATUS.

SPECIFICATION forming part of Letters Patent No. 409,751, dated August 27, 1889.

Application filed August 30, 1888. Serial No. 284,196. (No model.)

To all whom it may concern:

Be it known that I, JEREMIAH EUGENE MATHEWSON, of No. 265 Upper Thorpe, Sheffield, in the county of York, England, have 5 invented certain new and useful Improvements in Sand-Blast Apparatus, of which the following is a specification.

In the sand-blast apparatus as heretofore constructed the rapid destruction of the nozzle in which the propelling-fluid and the sand or cutting material are mingled before passing out of the apparatus has proved a great 10 obstacle to the economical success of the process of sharpening files and cutting stone, 15 glass, metals, and other substances by the sand-blast. This is due not only to the necessity for frequently renewing the nozzles, but also to the fact that the cutting action, which is at its maximum of efficiency at or 20 soon after the starting of the blast, becomes less and less efficient as the operation proceeds.

Now the object of the present invention is to remove these serious disadvantages and 25 thereby to effect an important economy both in the cost of maintenance of the apparatus and in the power and time required to produce a certain quantity of work.

It is well known that the abrasion of the 30 nozzles is due to the sand or other cutting material receiving its impulse while contained within the nozzle. By a series of experiments I have discovered that if the streams of propelling-fluid and sand or cutting material are 35 kept apart until they leave the blast-pipe, and if the steam or air on leaving the mouth-piece is caused to converge either to a central point or to a line in front of the mouth-piece and there strike the issuing stream of sand a 40 perfect mingling of the sand with the steam or air will take place and no cutting action will occur until the sand-blast meets the work.

I may use in carrying out my invention either a circular mouth-piece or a broad flat 45 mouth-piece, or forms intermediate of these, according to the work in hand, with the like beneficial result. I will first describe the invention as applied to a flat mouth-piece and afterward to a round mouth-piece.

50 In the accompanying drawings, Figure 1 shows in plan view, Fig. 2 in longitudinal

section, and Fig. 3 in front or end view, a mouth-piece such as I employ in finishing and sharpening files and rasps and working over broad surfaces; Figs. 4 and 5 show in longitudinal section and end view a circular mouth-piece suitable for general work such as cutting, frosting, and ornamenting glass and metallic surfaces or boring holes in glass and other materials, and Fig. 6 is a diagram which 60 illustrates the action of the invention.

Before describing the construction of the mouth-pieces I will, by reference to the diagram, Fig. 6, explain the manner in which the cutting material and the steam or air blast 65 are mingled at and beyond a point clear of the mouth-piece. In this diagram, 1 is the passage for the cutting material, and 2 2 are passages (on opposite sides of the passage 1) for the steam or air under pressure to pass out and 70 converge in a plane (indicated by the line 3 3) in advance of the passage 1. The streams of steam or air in thus converging will form a slight vacuum in front of the passage 1, facilitate the feed of the cutting material and 75 cause it to mingle with the impelling-fluid, as indicated by the dots in the diagram. Thus the mingling, instead of taking place, as heretofore, within the nozzle or mouth-piece and in contact with the metal, will occur in front of 80 the mouth-piece, and thereby the abrading action, so detrimental to the efficiency of the apparatus, will be avoided.

In Figs. 1 and 2, A is a casting forming the main portion of the mouth-piece, and 85 B B are plates bolted to opposite sides of the mouth-piece. In this casting A there is cored out a steam-passage a, which diverges from a cylindrical to a forked shape at a'. This forking of the steam-passage is produced by a transverse wall of metal, which 90 constitutes the back of a chamber C, that opens in the form of a slit c at the front of the mouth-piece. Access is obtained to this chamber by side openings in the casting A, for 95 the purpose of inserting therein a sand-tube D, connected with a reservoir for the sand or other cutting material. This tube D is preferably tapered toward its closed end, and at its back is formed a rib which enters a transverse slot cut in the back of the chamber to 100 insure its proper insertion in the mouth-piece.

The front of this tube D has a longitudinal opening covered by a flattened tube or parallel lips *d*, closed at their ends. Thus a passage is formed for conducting the sand from 5 the tube D to the slit or exit-opening *c* in the chamber C. By this mode of fitting the tube in place as little metallic contact as possible is established between the chamber and the tube. The object of this arrangement is to 10 prevent the heat of the impelling-fluid from so acting upon the cutting material (when wet sand or mud is used) as to choke the action of the apparatus.

The plates B B fit close upon slightly-raised 15 ribs at the sides of the casting A, and form at their back and sides steam-tight joints with the casting. These plates converge slightly toward the front of the mouth-piece, and serve to form extension-passages *b b*, 20 from which the impelling-fluid issues in thin streams, converging at an angle of some fifteen degrees toward the plane of progress of the stream of sand or cutting material, where they meet the same and mingle therewith, as 25 above explained with reference to Fig. 6. The chamber C terminates in a straight mouth *c*, parallel with the exit-openings of the steam-passages *b b*. The mouth of the 30 passage *c* is flush with the exit ends of the passages *b b*, but its width is somewhat less than the width of those passages.

For the purpose of delivering the sand or cutting material freely from the mouth-piece, I employ pressure (by gravitation or otherwise) to insure the steady feed of the material through the apparatus; and to provide 35 against injury to the mouth *c* of the chamber C, any bruising or notching of which would detract from the evenness of the stream, I 40 form the plates B with lips, which overhang the openings for the issue of the steam without interfering with its travel. This provision, it will be understood, is simply a guard for maintaining the efficiency of the 45 apparatus against rough usage.

E E are detachable plates set at opposite ends of the outlet-passages *b b*, to prevent air entering between the streams of steam and interfering with the steady flow of the 50 cutting material. These plates, which are made preferably of steel, are held in place against the plates B by binding-screws, which pass through screwed lugs formed on the casting A.

F is a loop cast in one with the mouth-piece A, and intended to receive a "feeler" G, which beds upon a raised portion of the upper plate B, and serves as a support and testing-piece for the file or rasp presented to the action of 60 the sand-blast.

In the circular portion of the passage *a* a screw is cut to allow of the mouth-piece being secured to the steam-supply pipe. When steam is delivered to the mouth-piece, and 65 sand or other cutting material is admitted to the pipe D, a jet of mingled steam and sand will be formed beyond the mouth-piece, of a

shape roughly corresponding, when striking the work, to the exit end of the mouth-piece.

For general work I use a circular mouth-piece, the size of which will depend upon the work it is required to perform. Thus when a jet corresponding more or less with a pencil-point is required I propose to employ a circular mouth-piece with an air-exit of about one-third the diameter of that shown at Figs. 4 and 5, or, say, one-eighth of an inch outside diameter. In this case an annular jet is formed, which surrounds the extruded feed of cutting material and strikes it at a point beyond the mouth-piece, mingling with the cutting material and producing an incisive jet, the diameter of which will increase according to the distance from the point of concentration at which the jet strikes the work. 85

In Figs. 4 and 5, H is a straight tube in communication with a reservoir of dry sand or other cutting material, which is supplied by gravitation to the tube H. This tube fits into the center of a tubular casting I, which terminates on a level with the exit end of the tube H, and is supplied with steam or air under pressure through a branch I' in communication with a steam-boiler, or air-pump, or reservoir, as the case may be. The steam or air entering the tubular casting I surrounds the tube H and passes out in the form of a hollow tapering jet, drawing with it a stream of sand or cutting material which meets the steam or air at a point in advance of the mouth-piece, 100 as in the first-described arrangement. Here the sand and the steam or air unite, and mingling, as illustrated in the diagram, Fig. 6, 90 form a cutting-blast, which, when presented to a metallic or other surface will abrade it, 105 either evenly in the form of lines or hard or softened shadows, the distance between the point of concentration of the steam or air and sand and the surface of the plate under treatment being varied to produce these varying 110 results, according to the nature of the work in hand.

I may remark that by slightly retracting the sand-tube H within the tube I, when that tube takes a cylindrical form at its exit end, 115 a converging jet may be obtained to operate upon the protruded sand or cutting material; but the efficiency of this arrangement as compared with that just described is not such as to recommend its adoption. 120

Where in the claim I use the word "sand" it will be understood that I do not mean to refer only to small particles of silicious material, but to any mass of small hard particles such as are capable of being used in the sand-blast, and by the word "fluid" I intend to refer to any fluid, whether in a liquid, gaseous, or vaporous form—as, for instance, water, air, or steam—all of which have been successfully used in the sand-blast; and in referring to the 125 passages which inclose the sand-passage I of course intend to include a construction in which a continuous passage incloses the sand-tube, as well as a construction in which the 130

inclosing-passage is broken by partitions or arranged in two parallel lines.

Having now described my invention, I declare that what I claim is—

- 5 In a sand-blast apparatus, the combination of a sand-passage with passages for the impelling-fluid arranged to substantially inclose

the sand-passage and inclined to it so as to converge toward the sand-jet and to a point in front of and clear of the mouth-piece.

J. E. MATHEWSON.
